UNITED STATES PATENT OFFICE

GEORGE W. SWAN, OF SAN FRANCISCO, CALIFORNIA.

IMPROVEMENT IN VENEER KEGS.

Specification forming part of Letters Patent No. **141,963**, dated August 19, 1873; application filed June 18, 1873.

To all whom it may concern:

Be it known that I, GEORGE W. SWAN, of San Francisco city and county, State of California, have invented an Improvement in Veneer Kegs; and I do hereby declare the following description and accompanying drawings are sufficient to enable any person skilled in the art or science to which it most nearly appertains to make and use my said invention without further invention or experiment.

My invention relates to a strong and durable keg, which is suitable for containing all kinds of articles and substances not under pressure that it is customary to place in kegs. The body of my improved keg is made out of one or more thicknesses of veneers or thin boards of wood upon a circular form, and having its edges secured together, the whole being covered with a layer of textile fabric, and treated with some mucilaginous substance. The heads are made of thick pieces of wood, inserted in each end of the cylinder and firmly fastened with nails.

In the accompanying drawing, A represents the body of the keg. This body is made of a single veneer, of the desired thickness and size, bent into a circular form. Its meeting edges are then firmly fastened by any suitable means, so as to form a true cylinder. A

head is then introduced into one end of the cylinder. I then usually apply to the interior of the cylinder or keg a lubricant, which will penetrate the veneer body. I then take a piece of canvas or other strong cloth or fabric and wrap it entirely around the cylinder or body of the keg, so that the edges overlap each other. The loricate, if of the proper kind, will fix the covering or fabric closely to the veneer; but, if necessary, a special cement or other adhesive can be used. The other head of the keg is then put in, and the keg is ready for use.

A keg constructed in this manner will be found to be strong enough for all ordinary purposes, while it can be constructed at a very small expense.

Having thus described my invention, what I claim, and desire to secure by Letters Patent, is—

As a new article of manufacture, the keg herein shown and described.

In witness whereof I hereunto set my hand and seal.

GEORGE W. SWAN. [L. S.]
